UNITED STATES PATENT OFFICE

2,217,127

COPYHOLDER

Earl H. Metcalf, Ridgefield Park, N. J.

Application July 15, 1938, Serial No. 219,330

1 Claim. (Cl. 120—34)

It is the principal object of this invention to provide a device of this character for holding loose sheets and bound copy books in a position convenient for reading; and at the same time progressively indicating, by means of a movable line indicator, each line of written copy.

A further object of this invention is to provide a copyholder of a simple, efficient and durable construction which may be made of any suitable material in different shapes and sizes.

With these and other objects in view, the invention consists in the novel features and combination of parts hereinafter described and claimed.

In the accompanying drawing,

Figure 1 represents a front elevational view of a copyholder constructed and arranged in accordance with my invention.

Figure 2 is a side elevation view of the backing plate of the copyholder as it appears with the line spacer in operating position in relation to the reciprocal rack.

Figure 3 is a sectional view of the carriage showing the recessed braking mechanism.

Figure 4 is a side elevation view showing a section of the reciprocal rack with the line space lever disconnected therefrom and folded to inoperative position.

Loose leaf copy is clamped in reading position against the face of the copy backing plate 1 by means of paper retaining fingers 2 mounted on a shaft 3 on one end of which is a spring 4 the function of which is to hold the paper retaining fingers 2 under tension against the face of the backing plate 1 having feet shod with rubber as shown at 1—a. It will be understood that the backing plate 1 may be provided with any suitable means (not shown, since it forms no part of the invention) for supporting it in a slightly inclined position upon a desk or table.

The line indicator 6 is rigidly attached to a carriage 8 slidable upon a guide rod 10 which is spaced from and fixedly secured to the backing plate 1 by the studs 7. The carriage 8 has a tubular extension 9 containing a recess wherein is located a friction member such as a ball 9—a, a compression spring 9—b and an adjusting screw 9—c for regulating the pressure of the ball 9—a on the guide rod 10.

A spring-actuated pawl 11 is pivotally mounted on the screw 11—a on the side of the carriage 8; and this pawl, under the influence of spring 11—b, is caused to engage the teeth of a reciprocal rack 12 which imparts steps of movement to the carriage, the length of said steps of movement

being predetermined by the position of the stop 14 pivoted on a screw 14—a extending into the lower end of the reciprocal rack 12. Although the pawl 11 engages the teeth of the reciprocal rack 12 to impart movement to the carriage in a downwardly direction, it will be observed that the rack 12 is free to move upwardly under the action of its associated return spring 13 without displacing the carriage which is frictionally retained on the guide rod 10 by the means hereinbefore described. It will be noted that said toothed rack 12 is provided with slots 12—a through which extend the screws 14—b and 14—c which are secured to the backing plate 1 and reciprocatively support the rack 12 on and parallel with the edge of the backing plate 1.

Rigidly attached to the backing plate is a hanger 16 in which is pivoted a line space lever 15 having an end 15—a adapted to be engaged by the user's finger. A pin 17 set into the spacing lever 15 is positioned to engage and lock in the slot 18 in the reciprocal rack 12 when said rack is located at either one or the other extreme terminus of its movement.

The paper to be copied is secured to the copy backing plate 1 by the retaining effect of the fingers 2. The line indicator 6 is then moved to a position directly below the first line to be copied, this being readily accomplished by moving the pawl 11 out of engagement with the rack 12, by engaging the outer end 11—c of the pawl with a forefinger and the extension 8—a of the carriage with the thumb of the operator's left hand. Thereafter, after copying each line of the paper to be copied, the operator depresses the spacing lever 15 with the result that the rack 12 is reciprocated downwardly and carries with it the carriage 8 carrying the line indicator 6; and when the lever 15 is released the rack 12 returns to its upper position.

It will be understood that when the stop 14 is in the position shown in Fig. 2, actuation of the lever 15 will cause the line indicator 6 to move a distance equal to the distance between lines of what is known as single-space typewriting; and that when said lever 15 is swung in a clockwise direction (as viewed in Fig. 2) so that the notched portion 14' of the lever engages the screw 14—b, depression of the lever 15 will cause the rack 12 and the line indicator 6 to move downwardly a distance equal to the space between lines of what is commonly called double-space typewriting.

Without limiting myself to details of construction which may be varied within the scope of my

40

50

55

invention, what I claim as new and desire to secure by Letters Patent is:

In a copyholder, a backing plate, a toothed rack having slots therein, screws extending 5 through said slots and into the edge of said backing plate for reciprocatively supporting the rack directly on, and parallel with one edge of the backing plate, a guide rod rigidly attached to said backing plate, a carriage slidably and rotatably mounted upon the guide rod, a spring actuated pawl pivotably mounted on the carriage and adapted to engage the teeth of the reciprocal rack whereby a step of movement is imparted to the carriage by the downward movement of the reciprocal rack, an adjustable braking means recessed 10 in the carriage to prevent movement of the carriage upon the return or upward movement of the reciprocal rack, a line indicator rigidly mounted

upon the carriage and movable therewith, means facilitating releasing the pawl from the teeth of the rack to permit the free movement of the carriage on the guide rod, a lever mounted on the backing plate and engaging the reciprocal rack, 5 said lever being operable to effect movement of the reciprocal rack throughout a complete step of movement in one direction, a spring attached to one end of the reciprocal rack to return said rack to its normal position for beginning its next 10 step of movement, a plate containing graduated steps pivoted upon one end of the reciprocal rack and engaging one of said screws to regulate the distance that the reciprocal rack may return after being actuated downward by the spacing lever, 15 thereby regulating and predetermining the length of steps of its movement.

EARL H. METCALF.
